UNITED STATES PATENT OFFICE.

THOMAS E. TAYLOR, OF MANSFIELD, OHIO, ASSIGNOR TO THE TAPPAN STOVE COMPANY, OF MANSFIELD, OHIO, A CORPORATION OF OHIO.

STOVE FRAME.

Application filed February 16, 1923. Serial No. 619,403.

To all whom it may concern:

Be it known that I, THOMAS E. TAYLOR, a citizen of the United States, residing at Mansfield, in the county of Richland and State of Ohio, have invented certain new and useful Improvements in Stove Frames, of which the following is a specification.

My invention relates to improvements in stove or range frames, and more particularly to the main front or oven door and door hinge carrying frame used in such ranges.

The primary object of the invention is to provide a generally improved main front or oven door frame made up of sections arranged and connected in an improved manner and resulting in economy in manufacture, use and repair.

A still further object is the provision of a front door or oven frame having sections providing certain advantages in the assemblage and disassemblage of the parts as well as providing a certain flexibility at the joints of the sections, thereby lessening the liability to damage or breakage while in use as well as facilitating the replacement of worn or broken parts.

A still further and very important object is the provision of improved hinge boxes or mountings for the oven doors so that the doors and hinge boxes or mountings and springs may be readily mounted in proper position or be removed entirely from the outside of the range, thereby eliminating the necessity of removing oven linings or getting into the inside of the oven as now required with the ordinary forms of oven door frames and hinge mountings.

A still further object is the provision of an improved oven door frame made up of improved under channelled side and cross members suitably strengthened and reinforced at the bolt receiving openings thereof through the medium of transverse or cross ribs arranged about said bolt receiving openings and within such channelled portions of said frame.

With the above mentioned and other ends in view, the invention consists in the novel construction, arrangement and combination of parts, hereinafter described, illustrated in one of its embodiments in the accompanying drawings, and particularly pointed out in the appended claims.

Referring to the drawings, forming a part

of this specification, Figure 1 is a perspective view of the oven portion of a stove of the range type equipped with an oven door and door hinge carrying frame constructed in accordance with this invention.

Fig. 2, an enlarged front elevation of the same, detached, the frame sections being in disassembled relation for the purpose of clearer illustration of the parts.

Fig. 3, a fragmentary perspective view of the jointed hinge carrying portion of the same.

Fig. 4, an enlarged cross sectional view of the same taken on line 4-4 of Fig. 2.

Similar numerals of reference designate like parts throughout all the figures of the drawings.

The improved oven door frame is of cast metal and comprises a main door section 1, and extension door sections 2.

The main section 1 is preferably of rectangular form, as shown, and comprises the under channelled side members 1 and cross members 1^a. The members 1 and 1^a of the main door section or frame are preferably provided about their inner marginal edges with an inset marginal edge or flange *a*, to receive and form a seat for the marginal edges of the main or baking oven door 3, when the latter is closed, as shown in Fig. 1 of the drawings.

The lower or extension frame sections 2, are adapted to form the sides of the lower or broiler door opening and to receive the marginal edges of the lower or broiler door 4, and these vertical frame members 2 are likewise provided with inset marginal portions *b*, to receive the edges of the door 4, the lower edges of the cross or intermediate member 1^a being provided with a marginal flange *c*, to form a seat for the upper edges of the lower or broiler oven door 4 when the latter is closed.

The channelled members of the frame sections 1 and 2 are provided with suitably spaced fastener element or bolt receiving openings *d*, and as a means of reinforcing the frame sections at such points, suitable cross or transversely extending reinforcing ribs *e*, are provided, said ribs extending across or filling the under channelled portions of the frame members and connecting the flange or web portions thereof, as shown most clearly in Fig. 4 of the drawings.

As a means of readily inserting or remov-

ing the oven door 3, or of readily changing any hinge box or spring, and of so doing without removing or disturbing the oven lining and without necessitating access to the inside of the oven, the lower corner portions of the main rectangular door section 1 are provided with hinge box receiving recesses 1^b, together with interiorly arranged bolts 1^c, and nuts 1^d, and said recesses 1^b are adapted to removably receive and contain suitable hinge boxes or casings 5, the upper portions of said hinge boxes 5 being provided with openings adapted to receive the outer ends of the fastening elements or bolts 1^c and to be held in position by the nuts 1^d. As a means of removably securing and retaining the lower edges of the hinge boxes or casings 5, the latter are provided with flanges 5^a and the lower or frame extension members or sections 2 are provided with corresponding undercut recesses 2^a and overhanging flanges 2^c, as shown most clearly in Fig. 3 of the drawings.

As a means of removably connecting the upper ends of the frame extension sections 2 to the lower stub or extension members 1^e of the main frame section, such members are provided with undercut recesses 2^b, corresponding in dimensions to the dimensions of the extension members 1^e so as to extend flush with the latter on the under sides, as shown most clearly in Fig. 3 of the drawings. As a means of connecting such extension sections 2 to the lower corner portions of the door section 1 and particularly to the depending or stub members 1^e, suitable screws 2^e, may be passed through the openings 2^f, (see Fig. 2) and through the corresponding screw receiving openings 1^f, of the frame portions 1^e.

As a means of removably receiving and carrying the hinge members or lugs of the lower or broiler door 4, the vertical members or sections 2 terminate at their lower ends 45 in hinge lugs 2^g, provided with suitable openings or bearing recesses 2^h, the lower ends of the lower oven door sections or members 2 being secured to the horizontal base band 6, of the stove frame by means 50 of attaching bolts or elements 7, as shown in Fig. 1 of the drawings.

Having thus described one of the embodi-

ments of my invention, without having attempted to set forth all the forms in which it may be made, or all the modes of its use, what I claim and desire to secure by Letters Patent is,—

1. In a range, an underchannelled transversely ribbed oven front frame of cast metal provided with bolt receiving openings.

2. In a range, an oven front frame of cast metal made up of a main rectangular frame section, and subjacent door forming frame extensions detachably secured to the lower side of said rectangular frame section.

3. In a stove, a rectangular oven door frame of cast metal provided with door hinge boxes, and detachable broiler oven frame members depending therefrom and terminating in hinge lug receiving members.

4. In a range, an oven front frame of cast metal made up of a rectangular baking oven door forming frame section, and broiler oven door forming extensions detachably secured to said oven door forming section.

5. In a stove, an oven door frame of cast metal comprising a rectangular frame provided with hinge box receiving recesses, hinge boxes in said recesses, and broiler oven frame members connected to said rectangular frame and extending over the lower portions of said hinge boxes.

6. In a range, an oven front frame provided with underchannelled side and cross members having bolt receiving openings, said underchannelled members being provided with cross ribs about said bolt receiving openings to reinforce the frame members at such points.

7. In a stove, an oven door forming frame comprising a main rectangular frame provided with hinge box receiving recesses, hinge boxes mounted in said recesses, and broiler oven frame extension members connected to said main rectangular frame and extending over and securing said hinge boxes in position.

In testimony whereof I have affixed my signature.

THOMAS E. TAYLOR.
